UNITED STATES PATENT OFFICE.

ALBERT VUILLEMIEUR, OF BRISTOL, CONNECTICUT, ASSIGNOR TO THE NEW DEPARTURE MANUFACTURING COMPANY, OF BRISTOL, CONNECTICUT, A CORPORATION OF CONNECTICUT.

GRINDING MACHINE.

Application filed May 16, 1923. Serial No. 639,227.

This invention relates to grinding machines and is herein shown as embodied in a machine for grinding balls.

In machines of this class it has been customary to employ grinding discs having grooves in which the balls are received and ground. Naturally, in such machines, the grooves wear deeper as the discs are continued in use, so that it has been necessary to stop the operation of the machine from time to time and dress down the faces of the ribs at the sides of the grooves in order to prevent the grooves becoming so deep that they perform little or no grinding. The discs are heavy and their separation for the purpose of subjecting them to the action of suitable dressing tools is laborious and a source of delay and expense.

An object of the invention, therefore, is to provide means for effecting the dressing of abrading discs with a minimum amount of labor, delay and expense. A further object is to provide improved means for effecting the dressing operation on a ball grinder without disassembling the parts of the grinder. Still another object is to provide improved means for effecting the dressing operation without the necessity for using any special dressing or truing tools.

In the illustrated construction, a fixed disc and a rotary disc having cooperating ball grooves are provided and provision is made for moving one of the discs into engagement with the other so that the mutual rubbing effects the truing operation. Preferably, one of the discs has a bearing in an eccentric bushing by means of which it can be moved out of axial alignment with the other disc. Consequently, the engagement of the ribs with one another is a combined lengthwise and crosswise rubbing such that the ribs are accurately re-surfaced.

To these ends and also to improve generally upon devices of the character indicated my invention consists in the various matters hereinafter described and claimed.

Referring to the drawings, Figure 1 is a vertical section through the machine.

Figure 2 is a section on the line 2—2 of Figure 1.

The numeral 10 designates a ball grinding disc, ring or plate carried by a plate 12 which is held against rotation in a suitable standard. The disc 10 has a plurality of

concentric ball grooves 14 between which lie the intervening ribs or lands 16. An abrasive disc or ring 18 having corresponding ball grooves and intervening ribs is detachably carried by the circular plate 20, the hub of which, as shown at 22, is threaded onto the end of a hollow spindle 24, driven by the pulley 26 which is keyed to the spindle as indicated at 28.

Surrounding the spindle are the single row bearing and the double row bearing 30 and 32, respectively, these being spaced by the sleeve 34. The bearings are mounted in an eccentric bushing 36 which is turnably carried by the standard or frame 38, a flange 40 on the bushing extending outwardly and limiting the movement of the bushing in one direction. A plate 42 attached to the other end of the bushing 36 prevents its axial movement in the other direction.

When the balls are in process of being ground, the parts are in the relative positions indicated in the drawings. When the ribs are to be re-surfaced, the disc 18 is moved laterally out of axial alignment with the disc 10. This is for the purpose of causing the rubbing engagement between the ribs on the discs to partake of both a longitudinal and a crosswise movement, the better to face the ribs. Fixed to or forming a part of the bushing 36 is a worm wheel 44 engaged by a worm 46 carried by a horizontal shaft 48 journaled in the standard and having a hand wheel 50 by which it may be turned. The normal alignment of the discs is preserved by means of a locking wedge and notch shown best in Figure 2. The notch 52 has inclined sides arranged to fit the inclined sides of the wedge 54 which slides radially in and out in a recess 56 formed in a boss on the standard 38. The locking wedge is moved by means of a bolt 58 threaded through the top of the boss and loosely connected to the wedge by means of a collar 60 set into a circular recess in the wedge. This wedge insures the re-positioning of the discs in accurate axial alignment after the facing or truing operation.

The disc 10, which is held against rotation, engages the balls yieldingly during the grinding operation. For this purpose a coil spring 62 is placed inside the sleeve 64 of the plate 12 and is interposed between the plate and an abutment (not shown) at the

other end of a rod 66. The rod 66 holds the discs against separation and passes through the hollow spindle 24, a nut 68 and washer 70 being fixed to one end. Upon removal 5 of the nut and washer, the shaft 66 is removable endwise through the discs for the purpose of allowing the necessary lateral movement of the disc 18 when the truing operation is performed. In some cases, 10 enough clearance may be left between the rod 66 and the spindle 24 to allow the lateral movement without removing the rod. To provide a yielding engagement between the discs during the truing or dressing 15 operation, the following mechanism is provided for constantly pressing the disc 10 against its companion disc. Rack teeth 72 are formed on the hub sleeve 64 and are engaged by a pinion 74, the shaft of which 20 may be squared to receive an arm 76 and the arm is yieldingly pulled in one direction by a spring 78 fixed to the end of the arm and to a fixed part of the frame.

It is believed that the operation of the 25 device is clearly apparent from the above description. Although the invention has been described and claimed by referring to a specific machine, it should be understood, that, in its broader aspects, the invention is 30 not necessarily limited to the apparatus selected for illustration.

I claim:

1. In a ball grinding machine, in combination, a disc, means for rotating the disc, a 35 second disc held against rotation, one of said discs having ball grooves with intervening ribs, and means for relatively moving the discs to cause one disc to engage the ribs on the other for dressing the latter, substantially as described.

2. In a ball grinding machine, in combination, a disc having ball grooves with intervening ribs, a second disc having similar ball 45 grooves with intervening ribs, means for causing a relative rotary movement between the discs to grind the work, and means for relatively displacing the discs to cause the ribs of one disc to engage with the ribs of the other for dressing the latter, substantially as described.

3. In a ball grinding machine, in combination, a disc having concentric ball grooves with intervening ribs, a second disc in axial alignment with the first and having similar 55 ball grooves with intervening ribs, means for rotating one of the discs to grind the work, and means for moving one of the discs

out of axial alignment with the other to cause the ribs on the two discs to mutually cross each other, substantially as described. 60

4. In a ball grinding machine, in combination, a disc having ball grooves with intervening ribs, a second disc having similar ball grooves with intervening ribs, means for rotating one of the discs to grind the work, and an eccentric sleeve furnishing a laterally movable support for one of said discs, substantially as described. 65

5. In a ball grinding machine, in combination, a disc having ball grooves with intervening ribs, a second disc having similar ball grooves with intervening ribs, means for rotating one of the discs to grind the work, a support for one of said discs, and means for laterally moving said support, 70 substantially as described. 75

6. In a ball grinding machine, in combination, a disc having ball grooves with intervening ribs, a second disc having similar ball grooves with intervening ribs, means for rotating one of the discs to grind the work, an eccentric sleeve furnishing a laterally movable support for one of said discs, means for turning said sleeve, and means for locking said sleeve in normal position. 80

7. In a ball grinding machine, in combination, a disc having ball grooves with intervening ribs, a second disc having similar ball grooves with intervening ribs, means for rotating one of the discs, a spring for yieldingly pressing the work between the discs, and a second spring for yieldingly pressing one of the discs against the other to grind one disc by contact with the other, substantially as described. 95

8. In a grinding machine, in combination, a disc, means for rotating the disc, a co-operating non-rotary disc, means for yieldingly pressing one of said discs against the other for grinding one disc by contact with the other, and independent means for yieldingly pressing the work between the discs, substantially as described. 100

9. In a grinding machine, in combination, a disc having concentric grooves, means for rotating the disc, a cooperating disc held against rotation, a rack and pinion for sliding said last named disc towards the other disc, and yielding means tending to turn the pinion to effect a grinding contact between the disks, substantially as described. 105

In testimony whereof I hereunto affix my signature.

ALBERT VUILLEUMIER.
